R. RHYON

SEWING MACHINE ATTACHMENT

Filed March 23, 1923

UNITED STATES PATENT OFFICE.

ROBERT RHYON, OF MONTREAL, QUEBEC, CANADA.

SEWING-MACHINE ATTACHMENT.

Application filed March 23, 1923. Serial No. 627,168.

To all whom it may concern:

Be it known that I, ROBERT RHYON, a citizen of the United States, and resident of the city of Montreal, in the Province of Quebec and Dominion of Canada, have invented certain new and useful Improvements in Sewing-Machine Attachments, of which the following is a full, clear, and exact description.

10 This invention relates to new and useful improvements in attachments for sewing machines, and the object of the invention is to provide an attachment which will automatically guide, feed and prepare for stitching together three pieces of fabric where one piece is to have a hem turned over another intermediate piece, such as a stiffening member and a third piece is to be stitched to the other members to form a lining or 15 facing therefor. The attachment is particularly adapted for use in making the waistband of trousers or the like.

In my invention I provide a sewing base plate for the machine with slots cut therein and placed in such a manner that the fabrics to be stitched together are led in the proper position for stitching, adjustable guides being provided to accommodate the various widths of fabrics to be used, said guides 20 being provided with top and bottom guards for this purpose. The binding member is attached to the underside of the sewing base plate and is adapted to lead the hemming cotton and double same over the stiffening 25 fabric before they are stitched together. The fabrics are wound on reels which are rotatably mounted in brackets attached to the main bed of the machine.

In the drawings:

40 Figure 1 is a perspective view of the attachment fitted to a sewing machine.

Figure 2 is a perspective view of the base plate.

Figure 3 is a perspective view of the hemming member.

Figures 4 and 5 are views of the guides.

Figure 6 illustrates the finished work.

Referring more particularly to the drawings, 11 designates the main bed of a sewing machine upon which is mounted the L bracket 12 supporting the head 13 of the sewing machine, in which the needle bar 14 is slidably mounted and operated in the well known manner. A sewing base plate 50 15 is mounted on pillars or distance pieces

16 through which, and the base plate, screws 17 are fitted into the bed plate. The pillars 16^a may be loosely mounted on the screw 17^a for reasons hereinafter described. Mounted on the bracket 18 which is attached to the bed plate is the reel 19 of stiffening fabric or canvas, the sides of the reel being adjustable to any desired width of canvas. Also attached to the bed plate by the bar support 20 are the reels of cotton fabric 21 60 and 22. The cotton fabric reels are rotatably mounted on the spindle 23 which fits into open ended slots 24 cut in the bar supports 20, the said slots being sloped so that any pull on the reels tends to hold the spindle 23 in position in the slots in the supports. The cotton on the reel 22 is used as the binding material and is led around the rotatably mounted pillar 16^a to a binding 70 or doubling member 25 which is secured by 75 a bent bar 26 to the underside of the sewing base plate. The doubling or binding member consists of a flat hollow piece of metal curved at one end 27 to receive the cotton 80 22 and it is doubled over about its longitudinal centre at its other end, so that the cotton will be doubled over when it is drawn through the said end. A slot 29 is cut in the base for the canvas or stiffening member 19 and is guided therethrough by the 85 guard 30 which is provided with guiding pieces 31 and 32, the piece 32 being placed below the base plate and the piece 31 being positioned above the base plate, both pieces being joined together by the narrow neck 33 which is made to turn easily in the slot for 90 dismantling. The binding member is so positioned that the canvas 19 passes between the folded edges 22^a of cotton before going through the slot 29. The cotton 21^a on the 95 reel 21 passes over the top of the base plate and is taken through the long narrow apertures 34 towards the needle 35. Guides similar to that shown in Figure 4 may be used or the pieces 31^a may be shortened to 100 prevent overlapping of the slots cut in the base. The guards are made adjustable to accommodate the widths of material used, elongated slots or apertures 36 being provided in the arm 36^a for this purpose, the 105 screws 37 passing through said apertures and screwed into the base plate. The apertures 34 are so positioned that the cotton 21^a is fed through the machine with one edge coinciding with one of the edges 22^a of the 110

binding cotton. The fabrics are then fed through the machine in the usual manner and stitched together by the threads 38. A hole 39 may be drilled in the base plate to accommodate the rack feed cover plate 40 or the slots 41 may be cut directly in the plate for the feeding mechanism and needle. In the drawing I have shown an attachment for stitching three pieces of fabric together but by slight modifications and cutting more slots in the machine base plate a greater number of fabrics may be automatically stitched together in the one operation. A starting slot 42 may be cut in the binding member to assist in guiding the binding cotton through the guide by hand.

The operation of the device is as follows: The reels are wound with fabrics of a desired width cut on the bias and are mounted in the brackets on the bed plate of the machine. The canvas or stiffening member is taken under the base plate and through the slot nearest the doubled end of the doubling member. The binding cotton is taken from the reel around the rotatable pillar through the flat end of the doubling member and then through the doubled end folding itself over the edge of the canvas before passing through the same slot as the canvas to the upper surface of the base plate. The facing cotton is first taken over the top of the base plate through one slot to the under side of the said plate and then through another slot back on to the upper surface of the plate and so guided that one edge of the cotton coincides with one of the edges of the binding cotton. The reason for passing the cotton through the double slots is that they provide a tension for the feeding of said cotton. The three pieces are then fed towards the needle in the usual manner and stitched together as shown in Figure 6 of the drawings.

This attachment is a great saving as regards time expended for operating and also material used, the operation being entirely automatic in its action and only needs the attention of an operator when setting up. The material is cut to the exact width and needs no trimming when taken from the machine. The guards are provided with guiding pieces, one above and one below the base plate, to keep the material in perfect alignment when passing through the machine. They are also placed as near the needle bar as possible and when the guard extends over the bound stiffening member as shown in Figure 1, a recess is cut as shown in Figure 4 and designated 43, to allow the guard to be bolted to the base plate and yet allow free movement of the stiffening member under it.

This attachment may be used for double curtains for trousers.

Having thus described my invention, what I claim is:—

1. An attachment for sewing machines comprising a base plate adapted to be mounted above the bed plate of a sewing machine, a plurality of reels for fabric rotatably mounted on brackets attached to the bed plate, a doubling member secured to the underside of the base plate and adapted to receive fabric from one of the reels, said base having a slot for the passage of a stiffening fabric which is bound by the doubled fabric before passing through the slot, and long narrow apertures in the base plate for the remaining fabrics and means to guide and position all the fabrics through the slots. 70 75

2. An attachment for sewing machines comprising a base plate mounted above the bed plate of a sewing machine, a plurality of reels for fabric rotatably mounted on brackets attached to the bed plate, said bed plate having a slot adapted for the passing of one of the fabrics, a doubling member, means to secure the doubling member to the underside of the base plate, and so positioned that one edge of the stiffening member is bound by the doubled fabric before passing through the slot, a guard with top and bottom guides for positioning said bound stiffening member, said base plate having other slots for the remaining fabrics, guards with top and bottom guides situated in said slots 90 95 to hold the fabrics in position and adjusting means for altering the positions of the guards to suit varying widths of fabric. 95

3. In a sewing machine attachment, a base plate, pillars for supporting said base plate, a hollow doubling member situated under said base plate adapted to receive fabric led around one of said pillars, and a slot cut in the base plate situated near the doubled end of the doubling member. 100 105

4. In a device of the character described, a base, means to support said base, a doubling member attached to and situated on the underside of said base, said base having a slot situated in close proximity to one end of said doubling member and elongated apertures, guards adapted to fit in said apertures, having top and bottom guides connected together by a narrow neck, to allow the guard to be fitted in said apertures, the top guides being above the base and the bottom guides being below the base, and means for adjusting said guards. 110 115

In witness whereof, I have hereunto set my hand.

ROBERT RHYON.
